UNITED STATES PATENT OFFICE

2,403,126

RINSE WRINGER

Albert Schellenberg, Joliet, Ill.

Application May 2, 1941, Serial No. 391,487

2 Claims. (Cl. 68—22)

1

This invention relates to wringers of the type used in connection with motor driven domestic washing machines, and particularly to that type of wringer wherein a rinsing operation is performed. This application is an improvement on the rinse wringer set forth in my co-pending application, No. 368,159, filed December 2, 1940, now Patent No. 2,358,256, granted Sept. 12, 1944.

The particular object of the present invention is to provide improved conveyor and rinsing means in the rinse chamber of the wringer.

Other objects and benefits will be disclosed in the following descriptions and drawing, in which

Fig. 1 is a cross-sectional elevation view of a rinse wringer having a conveyor carried on eccentric rollers mounted between two sets of rolls.

Fig. 2 is a similar cross-sectional elevation view showing a wringer having a hydraulic conveyor consisting of angular jets as will later be explained.

Fig. 3 is still another similar cross-sectional view showing a wringer having a conveyor consisting of multiple rollers assisted by angular spray jets.

It will be understood that all wringers, shown somewhat diagrammatically in the foregoing drawings, employ the reversible gear head driving the rolls and conveyor mechanism, the safety pressure release for the upper frame, the clutch to stop operation of the rolls and conveyor when pressure is released, the rinse basin overflow, and generally all necessary mechanical structure shown in the aforesaid application, Serial No. 368,159, together with any necessary modifications of this structure as could be accomplished by skillful mechanics experienced in the art. It will be appreciated that the present application deals with detailed modifications of structure with the basic mechanism of the wringer remaining practically the same as shown in the aforesaid application, Serial No. 368,159.

Now referring to the drawing, I designate the lower frames by the numeral 10 and the upper frames by the numeral 11. The dual pairs of driving rolls are designated 14—15 and 16—17. The water level in the rinse chamber in each case is designated by the letter L.

Now referring to Fig. 1, I show a wringer having a belt 18 mounted on eccentric rollers 20—21. By the movement of the belt as actuated by the eccentrics, a walking rake action is created which

will effectively move the clothes through the rinse chamber. The belt 18 may have perforations 18' or rubber fingers 19 to assist in this movement, as well as to create agitation of water in the rinse chamber to agitate and flush the clothes with the rinse water in the basin, as well as that supplied by the spray tube S1.

Fig. 2 shows another species of wringer wherein the conveyor means is hydraulic. The hollow head 22 in the rinse basin is supplied with water under pressure from the pipe 24 either from city water pressure or from a pump power driven from the wringer gear head. Angular jets 23 in the hollow head 22 impinge against the clothes, agitating and moving them forward through the rinse water and into the rolls 16—17.

In Fig. 3 I show another species of wringer wherein the conveyor means is by rollers 30—31—32 mounted in the rinse basin as above. These rollers may be either plain or corrugated as at 30', cam shaped as at 31', or having multiple rubber fingers as at 32'; in fact, the rollers may be of any desired shape to agitate and urge the clothes forwardly through the discharge rolls 16—17. In order to keep clothes from falling through the rollers into the bottom of the rinse basin, I provide baffles 33—34—35—36 between the rollers. Movement of the clothes is also assisted by angular jets from the tubes S2 and S3 as shown. These jets drive the clothes downwardly against the rollers into contact with the rollers where they will be agitated and urged forwardly through the discharge rolls 16—17.

Having thus described my invention, I claim:

1. In a rinse wringer, a rinsing chamber, a pair of intake rolls at one end of the rinsing chamber, a pair of discharge rolls at the opposite end of the rinsing chamber, conveyor means in the rinsing chamber including a belt carried on eccentric rollers to agitate and rinse garments as they are moved through the rinse chamber, and spray rinse means in the rinsing chamber to maintain a water level therein.

2. In a rinse wringer, a rinsing chamber, conveying means in the rinsing chamber including a belt for conveying garments through the rinsing chamber, and eccentric rollers supporting said belt to agitate the garments as they move through the rinsing chamber.
